UNITED STATES PATENT OFFICE.

GEORGE DAVIDSON AND RICHARD ADDERSON DIXON, OF PARIS,
ONTARIO, CANADA.

CIRCULAR-KNITTING MACHINE.

SPECIFICATION forming part of Letters Patent No. 427,465, dated May 6, 1890.

Application filed August 6, 1888. Serial No. 282,068. (No model.)

To all whom it may concern:

Be it known that we, GEORGE DAVIDSON and RICHARD ADDERSON DIXON, both manufacturers, and both of the town of Paris, in the county of Brant, in the Province of Ontario, Canada, have jointly invented certain new and useful Improvements in Circular-Knitting Machines, of which the following is a specification.

10 The object of the invention is to design a simple attachment by which an auxiliary thread is instantaneously thrown into connection with the needles should the ordinary thread be broken or subjected to an undue 15 tension strain; and it consists, essentially, of a tension-lever carrying the ordinary thread and supported by a spring of only sufficient strength to resist the ordinary tension on the thread in such a manner that should the tension be increased beyond the desired strain the said lever will drop and in its downward motion cause a pivoted thread-carrier to bring an auxiliary thread into contact with the burr or sinker wheel of the machine.

20 Figure 1 is a perspective view of the mechanism involved in our invention set for the knitting of the ordinary thread. Fig. 2 is a perspective detail on an enlarged scale.

In the drawings, A represents the needles 30 of the machine, B the burr or sinker wheel, and C the carrier for directing the ordinary thread D. The carrier C is supported by a bracket E' vertically adjustable on the post E by means of the slot b and set-screw c, this 35 being a common method of adjustment. F F' are two jaws, one jaw F' being rigid with said bracket, the other jaw F being secured to the bracket by a screw G, the loosening of which will remove the pressure of the jaw F 40 against the carrier C and permit the said carrier to be adjusted longitudinally in order to direct the thread D toward the proper point for feeding it into contact with the burr or sinker wheel B.

45 H is a weighted tension-lever pivoted in a suitable bearing formed upon or attached to the carrier C, and J is a spring projecting below or held in contact with the lever H with only sufficient force to resist the ordinary tension on the thread D. This thread, it will be

noticed, passes below the lever H and is supported in a loop formed in the finger K, which is attached to and extends below a head formed on the lever H.

L is a lever pivoted at a and bent so as to 55 extend over the thread D, the said lever L being preferably made of light wire, so that it may be readily supported by the thread D without interfering with the free passage of the said thread through the machine.

M is what we term an "auxiliary" thread, passing through a loop N, formed in the end of the rod O. After passing through this loop N the thread M is carried over a notch formed in the end of a finger T, carried by the free 65 end of the rod O, as shown in Fig. 2, and projecting below the burr or sinker wheel B, so that a loop of the thread will be carried below the said burr or sinker wheel. A rod P is connected to the rod O or to the rocking shaft 70 O', to which one end of said rod is connected, as shown, and extends back to rest upon a bent finger Q, formed upon or attached to the lever L. When thus supported, the thread M is held clear of the burr or sinker wheel B. 75 Should the thread D break, the lever L would instantly drop. Consequently the bent finger Q would be carried away from the end of the rod P, thereby permitting the said rod to drop and cause the rod O to rise and carry 80 with it the thread M into contact with the burr or sinker-wheel B.

We prefer to make the rods O and P independent of each other, although both must be connected to the same pivot. By making 85 them independent of each other they can be each longitudinally adjusted to suit the requirements of their employment, (see Fig. 2,) set-screws p' being provided to hold said rods in their adjusted positions. A spring R may 90 be applied to the rod P for the purpose of forcing it down when not supported by the finger Q, or a weight on the end of the said rod P might be substituted, as shown in dotted lines in Fig. 2.

95 Our invention also provides for the auxiliary thread M to be thrown into connection with the burr or sinker wheel B should the strain on the thread D be greater than the desired tension. In this event the tension-

lever H will be forced down past its spring J, and in thus falling, as it carries the lever L with it, the finger Q will be carried clear of the end of the rod P, which will thus act in 5 the same manner as though the thread D were broken. When the lever H is thus caused to fall by an extra strain on the thread, the weighted head on the said lever strikes the knife U, carried by the carrier C between the 10 pivots of the levers H and L and rods O P, cutting the thread D and leaving the work to be filled in by the auxiliary thread M.

It will be noticed that the thread D passes through an oblong hole c', formed in the end 15 of the carrier C. This oblong hole is made sufficiently large to permit the free passage of any ordinary chip or burr usually found on yarn. By thus forming an oblong hole we avoid breaking the thread by a chip or burr 20 being held in the hole.

In order to prevent the rod P falling farther than is required for the purpose of bringing the thread M into contact with the burr or 25 sinker wheel B, we provide a stop V, projecting below the rod P and vertically adjustable upon the carrier C by means of the screws d engaging the loop e in said stop.

What we claim as our invention is—

1. The combination, with the carrier, of 30 the tension-lever pivoted thereon, a spring supporting said lever and of only sufficient strength to resist the ordinary tension on the thread, the lever L, and an auxiliary thread-carrier pivoted between the end of the carrier 35 and the tension-lever and provided with an arm normally supported by a finger on said lever L and the knife U, substantially as shown and described.

2. The pivoted rod O, having a loop N 40 formed on its end, and a finger T, projecting from the said loop below the burr or sinker wheel of the machine, so as to support a loop of the auxiliary thread below the said burr or sinker wheel, a rod P, connected to the 45 pivot of the rod O and extending to a point where its end may rest upon the finger Q, which is connected to the pivot a, in combi-

nation with the lever L, carrying said finger Q and connected to the said pivot a, and designed to rest upon the ordinary thread, substantially as and for the purpose specified. 50

3. A lever L, a tension-lever H, carrying the ordinary thread and supported by a spring J of only sufficient strength to resist the ordinary tension on the thread, in combination 55 with the burr or sinker wheel, the knife U, and a pivoted thread-carrier arranged to support the auxiliary thread below the burr or sinker wheel B, substantially as described, whereby any excess of a predetermined tension on the thread D shall cause the lever H to fall, and thereby impart movement to the thread-carrier and simultaneously cut the thread by the action of the knife U, substantially as and for the purpose specified. 60

4. The combination, with the post E, of the bracket E' on said post, the jaw F', rigid on said bracket, the jaw F, adjustable thereon, and the carrier held between said jaws, substantially as and for the purpose specified. 70

5. The combination, with the tension-lever H, carrying the ordinary thread and supported as described, and the lever L, of a finger Q, carried by said lever L, the rocking arm O, carrying an auxiliary thread, the knife U, and the arm P, rocking with said arm O and normally supported by said finger, substantially as described. 75

6. The combination, with the tension-lever H, carrying the ordinary thread and supported as described, and the lever L, of a finger Q, carried by said lever L, the rocking arm O, carrying an auxiliary thread, the knife U, and the arm P, rocking with said arm O and normally supported by said finger, and 80 the adjustable stop V for said arm P, and the screws holding said stop in its adjusted position, substantially as described. 85

Paris, July 23, 1888.

GEORGE DAVIDSON.

RICHARD ADDERSON DIXON.
